UNITED STATES PATENT OFFICE.

ISAAC A. HERRMANN, OF ELYRIA, OHIO.

WATCHMAN'S RECORDING-CLOCK.

1,231,350.

Specification of Letters Patent. Patented June 26, 1917.

Application filed September 20, 1915. Serial No. 51,545.

To all whom it may concern:

Be it known that I, ISAAC A. HERRMANN, a citizen of the United States, residing at Elyria, in the county of Lorain and State 5 of Ohio, have invented a certain new and useful Improvement in Watchmen's Recording-Clocks, of which the following is a full, clear, and exact description, reference being had to the accompanying drawings.

10 This invention relates to recording clocks and particularly to the kind of clocks used by nightwatchmen and patrolmen to enable them to record with certainty and accuracy the fact of their being at their post of duty 15 at a given time but to prevent either them or any one else from going over the record at any time and filling in blanks, or from opening the device and obtaining access to any part thereof without leaving a record of 20 the same. A subsidiary object of the invention is the provision of means for preventing the making of a record excepting during that portion of the day during which the watchman is on duty and from preventing 25 any day's record from becoming exposed until that day has arrived. Other objects of the invention relate to the construction whereby a simple, economical and reliable device is produced, while additional objects 30 and advantages will become apparent as the description proceeds.

Generally speaking my invention may be defined as consisting of the combinations and constructions recited in the claims annexed hereto and illustrated in one embodiment in the drawings accompanying and forming a part of this application, wherein Figure 1 is a front elevational view of the complete device in operating condition, the 35 full lines showing the shield swung aside to permit the making of a record and the dotted lines showing the shield closed and locked in place; Fig. 2 is a view drawn to enlarged scale showing my improved recording 40 clock with the cover thrown wide open to disclose the interior construction; Fig. 3 is a cross sectional view taken immediately inside the closed cover of the casing, a portion of the rotatable shield being broken away; Fig. 4 is a view of the device with the record 45 sheet removed and the cover swung half open so as to disclose its edge view; Fig. 5 is a detail view taken upon the line 5—5 of

Fig. 3 showing the lock in securing position; Fig. 6 is a detail view of the lock viewed 55 from the opposite direction from that shown in Fig. 5, the lock being shown in released position; Fig. 7 is a view similar to Fig. 6 showing the lock in intermediate position; Fig. 8 is a detail view showing the method 60 of securing the record sheet in place and for adjusting the shield moving member; and Fig. 9 is a perspective view of one form of recording tool.

Describing the parts by reference characters, 1 indicates a metal casing preferably of cylindrical shape and adapted to be secured against a wall or other convenient location in any suitable way as by interior screws 2—2. 3 indicates a circular cover 70 hinged to said casing in any suitable manner as by the lugs 4—4 and preferably having an overhanging rim 5 closely surrounding the casing. Carried by the interior of the cover at a point removed from the hinge 75 is a locking post 6 having therein an aperture 7, said post being arranged to enter the aperture 8 of a suitable lock and there to be engaged by the locking bolt 9.

Inside the casing I locate a suitable chronometer movement indicated generally at 12 (Figs. 4 and 5) having coaxial with the casing 1 a rotating spindle 13 terminating in a flat table 14. Secured to this table in any suitable manner so as to rotate therewith is 80 the record sheet 15, which is preferably of printed paper having the days of the week marked thereon in concentric circles and the hours from 1 to 12 marked thereon in radiating lines as shown in Fig. 2. One convenient mode of securing this sheet in place 85 is to provide the table 14 with a central boss 16 having pivoted thereto a cam lever 17 and to insert beneath said cam lever a slotted plate 18 afterward turning the cam lever 90 down thereon to the position shown in Fig. 2. Between the plate 18 and the surface of the paper I insert a flat washer 19 formed with a radial finger 20 whose purpose will be hereafter described.

Secured to the interior wall of the casing 1 and projecting radially inwardly immediately in the rear of the paper sheet is an anvil 25 having its forward face preferably provided with spaced depressions 26, and 105 formed in the cover opposite these depres-

sions is a row of apertures 27, one for each depression. The record is formed by inserting into one of the apertures 27 a key of the type shown in Fig. 9 so as to prick 5 or dent the paper into the corresponding depression 26, the time of this prick being recorded by the rotation of the disk, and the particular aperture open at the time being governed by the means now to be described.

Journaled to the inner face of the cover is a flat circular metal disk 30 having therein a plurality of apertures 31^a, 31^b, 31^c, 31^d, 31^e, 31^f, 31^g arranged so that as said disk is 15 rotated said apertures come one by one into alinement with the various apertures 27. Preferably one portion of the periphery of the disk is formed with V shaped notches 32 adapted to be engaged by the V shaped 20 spring 33 whereby the disk is held impositively in any position to which it is set. Another portion of the periphery of said disk is formed with ratchet teeth 34 adapted to be engaged by a pawl 35 carried at the end of 25 the swinging lever 36 pivoted at 37 to an arm 38 also carried by the cover and projecting across the inner face of said disk. Upon the opposite side of the pivot 37 from the pawl 35 said arm is formed with a horizontally 30 projecting finger 39 adapted to be engaged by the finger 20 upon the rotation of the spindle, thus displacing the arm 36 and advancing the disk one step. A counterweight 40 may be employed for returning 35 the arm to original position.

In order to prevent the opening of the casting without leaving a record thereon I provide means whereby the turning of the lock shall punch the paper, and the simplest expedient for this purpose which I have so far devised is that shown in Figs. 3, 5, 6 and 7. According to this construction the lock consists of a plate 45 having journaled therein a rotatable stud 46 furnished with a 45 radial arm 47, the end of which is bent circumferentially to form the locking bolt 9. Carried by the plate 45 is a slotted support 48 between the halves of which the record sheet passes as shown in Figs. 5, 6 and 7. Said support is also formed with a second slot 50 perpendicular to the paper, and pivoted upon the face of the plate 45 at one side of the stud 46 is a striker 51 having its free end turned as shown at 52 and provided 55 with a cutting edge adapted to be inserted into the slot 50 and to punch the paper at that point. Normally said edge is held in retracted position by suitable means such as a spring 53, while its forward movement can 60 conveniently be produced by means of a radial finger 54 on the stud 46 engaging a flexible feather 55 on the striker 51, whereby said striker will be rocked to the position shown in Fig. 7 after which the feather 65 slips off the finger and the striker is re-

tracted allowing the free removal of the record sheet. Upon turning the stud into locking position the finger 54 engages the feather 55 in reverse direction as will be obvious from an inspection of Fig. 6 whereupon the feather merely yields without displacing the striker.

The lower end of the anvil 25 is provided with an indication of some nature such as that shown at 58 to aid the setting of the dial. The inner face of the disk 30 is preferably covered by a bridge 59 spaced from the inside of the cover so as to permit the free rotation of the disk but serving to prevent deformation of the same as by catching 80 of the key therein. Apertures 59' are formed in the bridge 59 in alinement with the apertures 27 in the cover. At one side of the bridge 59 the disk 30 is provided with a stop pin 60 adapted to engage the side thereof at 85 a point one step beyond the first aperture 31^a; on the other side of said bridge the disk 30 is provided with a stop pin 61 adapted to engage said bridge when said disk has been turned one step beyond the aperture 31^g. 90 The exterior of the cover is preferably provided with a pivoted shield 62 which may be either swung aside to permit the insertion of the recording key or secured in place by the padlock 63.

With the construction herein described experience has shown that if the finger 20 be located in alinement with the eleven o'clock division of the dial, the disk 30 will be shifted one step each time that the six o'clock 100 division passes the point 58. This relation is utilized in setting the device in the following manner:—Supposing that a new record sheet is to be applied on Sunday afternoon at three o'clock; the record sheet is 105 placed with its three o'clock division in register with the pointer 58, and the washer 19 is located with its finger 20 in alinement with the eleven o'clock division of the sheet. The disk 30 is turned until the pin 60 engages the bridge 59, thereby leaving all of the apertures 27 closed, after which the cover is shut and locked. At six p. m. on Sunday the movement of the finger 20 shifts the disk 30 one step as heretofore explained, so that 110 until 6 o'clock Monday morning the watchman can insert his key through the aperture 31^a without obstruction, thus making a record all the way around the disk in case his visits are rightly timed. At six o'clock 115 Monday morning the movement of the finger 20 advances said disk another step so that all the openings are closed, which condition is retained until six p. m. Monday whereupon the movement of the disk opens the 120 aperture 31^b, permitting the second concentric record to be made while shielding the first record against mutilation or falsification. This continues until the end of the 125 week when the sheet will be entirely finished. 130

If the watchman or any other interested person should attempt to work the disk around by prodding it through the aperture 27 with a key or other tool, the most that they could do would be to advance the disk, thereby throwing the registration a day ahead and indicating clearly that the clock had been tampered with, but without the possibility of mutilating the record already made. In case the lock were manipulated to open the casing the record sheet would be punched in the manner heretofore described, and the angular relation of the punch and point 58 will invariably afford a clue as to the time of opening.

I am aware that important features of my improved clock can be employed without employing all of the same; also that many changes in point of arrangement and design can be made without departing from the scope of my inventive idea or losing the benefits of my invention. The expression "record receiving means" or "record receiving element" used in the claims is intended to cover any substance or surface capable of receiving a mark, cut, prick or stamp, whether of paper, cloth, metal, wax or other substance, and whether round, square, flat, convex, concave or warped; the expression "impressing" is intended to cover the production of any intelligible mark, whether by cutting, pricking, marking, stamping, with a tool, pencil or pin, by chemical or electrical means; the expression "series of apertures" is intended to cover either a series of spaced apertures or a series of apertures merging together so as to produce in effect an elongated slot; accordingly, I do not propose to limit myself to such details except as the same may be positively included in the claims hereto annexed or may be rendered necessary by the prior state of the art.

Having thus described my invention, what I claim is:

1. In a recording device, a shielding element, a record receiving element behind said shielding element, means operative from the front of said shielding element for impressing a record upon said receiving element, time controlled means for moving one of said elements relatively to the other element at a uniform speed, and means coöperating with said shielding element for progressively exposing to the operation of said record impressing means a limited portion of said record receiving element.

2. In a recording device, a shielding element having an aperture therein, a record receiving element behind said shielding element, time controlled means for moving one of said elements relatively to the other element at a uniform speed, means coöperating with said shielding element whereby said aperture is alternately covered and uncov-

ered, and means operative from the front of said shielding element for impressing a record upon said receiving element during that part of the time during which said aperture is opened.

3. In a recording device, an apertured shielding element, a record receiving element behind said shielding element, time controlled means for moving one of said record receiving elements relatively to the shielding element at a uniform speed, means for moving said shielding element whereby the exposed portion of said recording element is shifted in a direction at right angles to its chronologic movement, and means operative from the front of said shielding element for impressing a record upon said receiving element during that part of the time during which said aperture is opened.

4. In a recording device, a casing having an aperture in its face, a shielding element movably supported inside this casing and having an aperture therein adapted to register with said first aperture, a record receiving element behind said shielding element, means for moving said recording element past said first aperture at a uniform speed, means for moving said shielding element intermittently to bring said apertures into and out of alinement, and means adapted to traverse said apertures and impress a record upon said receiving surface during the time that said apertures are in alinement.

5. In a recording device, a casing having a series of apertures in its face, a shielding element movably supported inside this casing and having a series of apertures therein arranged at an angle to said first series of apertures and adapted to register, one by one, a record receiving element behind said shielding element, means for moving said recording element past said first series of apertures at a uniform speed, means for moving said shielding element relatively to said casing whereby different apertures of the two series may be brought into alinement, and means adapted to be inserted through alined apertures to impress a record upon said receiving surface.

6. In a recording device, a casing having a plurality of apertures in its front, a recording element within said casing, means for moving said recording element past said apertures at a uniform speed, a shielding element between the apertured part of said casing and said receiving element, means controlled by the movement of said receiving element for alternately moving said shielding element into and out of obstructing position, and means adapted to be inserted through said apertures when said shielding element is out of obstructing position to impress a record upon said receiving element.

7. In a recording device, a casing having a plurality of apertures in its front, a re-

- 5 cording element within said casing, means for moving said recording element past said apertures at a uniform speed, a shielding element between said apertures and said receiving element, means for moving said shielding element whereby the apertured portion of said casing may alternately be covered and uncovered, said shielding element being arranged so that upon each 10 unit covering movement a different part of said receiving element is exposed, and means adapted to be inserted through said aperture during the time that said shielding element is out of obstructing position for impressing a mark upon said receiving element.
- 15 8. In a recording device, a casing having a series of apertures in its wall, a record receiving element within said casing, means moving said element constantly past said apertures in a direction at right angles to the length of said series, a shielding element between said receiving element and the apertured side of said casing, said shielding element having a series of apertures arranged in a direction oblique to the direction of said first series, means for shifting said shielding device intermittently whereby different apertures of the two series may successively be brought into alinement with each other, and means adapted to be inserted through said apertures during the time that said shielding element is out of obstructing position for impressing a mark upon said receiving element.
- 20 9. In a recording device, a casing having a series of apertures in its wall, a record receiving element within said casing, means moving said element constantly past said apertures in a direction at right angles to the length of said series, a shielding element between said receiving element and the apertured side of said casing, said shielding element having a series of apertures arranged in a direction oblique to the direction of said first series, means for shifting said shielding element intermittently in a direction parallel with the direction of movement of said receiving element whereby different apertures of the two series may successively be brought into alinement with each other, and means adapted to be inserted through said apertures during the time that said shielding element is out of obstructing position for impressing a mark 25 upon said receiving element.
- 25 10. In a recording device, a casing having a series of apertures in its wall, a record receiving element within said casing, means moving said element constantly past said apertures in a direction at right angles to the length of said series, a shielding element between said receiving element and the apertured side of said casing, said shielding element having a series of apertures arranged in a direction oblique to the direction of said first series, means for moving said shielding device in step by step manner past said first series of apertures, the length of each step being one-half of that necessary to move said shielding element from a point 30 of alinement of one set of apertures to a point of alinement of the next set of apertures, and means adapted to be inserted through said apertures during the time that said shielding element is out of obstructing position for impressing a mark upon said receiving element.
- 35 11. In a recording device, a casing having a series of apertures in its wall, a record receiving element within said casing, means moving said element constantly past said apertures in a direction at right angles to the length of said series, a shielding element between said receiving element and the apertured side of said casing, said shielding element having a series of apertures arranged in a direction oblique to the direction of said first series, means operative by the movement of said receiving element for advancing said shielding element definite 40 steps at predetermined intervals, the length of each step being such that upon alternate steps successive pairs of apertures will be brought into alinement and upon intermediate steps all apertures will be brought out of alinement, and means adapted to be inserted through said apertures during the time that said shielding element is out of obstructing position for impressing a mark upon said receiving element.
- 45 12. In a recording device, a casing having a series of apertures in its wall, a circular record receiving element within said casing, means rotating said element constantly, said apertures being arranged in a direction such that the length of the series shall be radial to said element, a circular rotatable shielding element pivoted between said receiving element and the apertured side of said casing, said shielding element having a series of apertures arranged spirally of said first series, means for rotating said shielding device intermittently whereby different apertures of the two series may successively be brought into alinement with each other, and means adapted to be inserted through said apertures during the time that said shielding element is out of obstructing position for impressing a mark 50 upon said receiving element.
- 55 13. In a recording device, a casing having a series of apertures in its wall, a circular record receiving element within said casing, means rotating said element constantly, said apertures being arranged in a direction such that the length of the series shall be radial to said element, a circular rotatable shielding element pivoted between said receiving element and the aperture side of said casing, said shielding element having a series 55

- of apertures arranged spirally of said first series, and means for rotating said shielding element intermittently in the same direction as said receiving element, whereby 5 different apertures of the two series may be brought into alinement with each other, and means adapted to be inserted through said apertures during the time that said shielding element is out of obstructing position 10 for impressing a mark upon said receiving element.
14. In a recording device, a casing having a series of apertures in its wall, a circular record receiving element within said casing, 15 means rotating said element constantly, said apertures being arranged in a direction such that the length of the series shall be radial to said element, a circular rotatable shielding element pivoted between said receiving 20 element and the apertured side of said casing, said shielding element having a series of apertures arranged spirally of said first series, means for rotating said shielding device in step by step manner past said first 25 series of apertures, the length of each step being one-half of that necessary to move said shielding element from a point of alinement of one set of apertures to a point of alinement of the next set of apertures, and 30 means adapted to be inserted through said apertures during the time that said shielding element is out of obstructing position for impressing a mark upon said receiving element.
15. In a recording device, a casing having a series of apertures in its wall, a circular record receiving element within said casing, means rotating said element constantly, said apertures being arranged in a direction such 40 that the length of the series shall be radial to said element, a circular rotatable shielding element pivoted between said receiving element and the apertured side of said casing, said shielding element having a series 45 of apertures arranged spirally of said first series, means operative by the movement of said receiving element for rotating said shielding element definite steps at predetermined intervals, the length of each step being such that upon alternate steps successive pairs of apertures will be brought into alinement and upon intermediate steps all apertures will be brought out of alinement, and means adapted to be inserted through said 50 apertures during the time that said shielding element is out of obstructing position for impressing a mark upon said receiving element.
16. In a recording device, a casing having an aperture in one of its walls, a record receiving element rotatably mounted in said casing, means moving said element uniformly past said opening, a shielding element pivoted inside said casing between 55 said element and said apertured wall, said shielding element being pivoted substantially concentric with said receiving element and having a plurality of apertures arranged spirally, and means for intermittently advancing said shielding element whereby said spirally arranged apertures can be brought into alinement with different apertures of said first series. 70
17. In a recording device, a casing having an aperture in one of its walls, a circular record receiving element rotatably mounted in said casing, means for rotating said element once in twelve hours at uniform speed, a shielding element pivoted inside said casing between said element and said apertured 75 wall, said shielding element being pivoted substantially concentric with said receiving element and having apertures therein, pawl and ratchet means for advancing said shielding element, and devices movable with said record receiving element for operating said pawl and ratchet means, the angular distance between successive apertures in said shielding element being twice that of said ratchet means. 80
18. In a recording device, a casing, a rotating record receiving element within said casing, a rotatable shielding element pivoted inside said casing between said receiving element and the casing wall upon an axis substantially coincident with that of said rotating element, said casing wall being formed with a radial series of apertures and said shielding element with a spirally arranged series of apertures arranged to 85 register one at a time with said first apertures, means for rotating said first element continuously and said second element intermittently, and means adapted to be inserted through registering apertures to impress a mark upon said receiving element. 90
19. In a recording device, a casing having an aperture in one of its walls, a circular record receiving element rotatably mounted in said casing adjacent to said wall, means for rotating said element at a fixed speed, a finger rotatable with said element, an arm projecting into said casing adjacent to the face of said element, a shielding element journaled inside said casing between said arm and the casing wall, a movable lever pivoted to said arm and adapted to be engaged by said finger at predetermined intervals, means coöperating with said lever whereby said shielding member may be displaced upon the operation of said lever, said shielding member having one or more apertures therein adapted to be brought into register with said casing aperture upon certain displacements, and means adapted to be inserted through said apertures and to impress a record on said receiving element. 100
20. In a recording device, a casing having an opening in one of its walls, an anvil inside said casing and spaced from said open- 105

ing, a record sheet located in said casing between said opening and anvil, means for moving said sheet uniformly over said anvil, a shielding element supported adjacent to said opening, means for moving said shielding element for alternately covering and uncovering said opening, and an adjustable operating device moving with said record and adapted to engage said operating means and

shift said shielding member at predetermined times.

In testimony whereof, I hereunto affix my signature in the presence of two witnesses.

ISAAC A. HERRMANN.
